UNITED STATES PATENT OFFICE

ALFRED H. ZELEDON, OF CHICAGO, ILLINOIS, ASSIGNOR TO SCENE-IN-ACTION CORPORATION, OF CHICAGO, ILLINOIS, A CORPORATION OF ILLINOIS

DISPLAY DEVICE

Application filed June 10, 1931. Serial No. 543,331.

My invention relates to an improvement in display devices and has for one purpose the provision of a display device which shall consist of or include a picture having fixed parts and moving parts, the moving parts giving the appearance of actual motion during the actuation of the device. One object is the provision of a display device of the type described, in which the number of parts shall be reduced. Another object is the provision of such a device in which the appearance of motion shall be improved in its realism. Other objects will appear from time to time in the course of the specification and claims.

15 I illustrate my invention more or less diagrammatically in the accompanying drawings, wherein—

Figure 1 illustrates a side elevation with parts broken away;

20 Figure 2 is a section on the line 2—2 of Figure 1;

Figure 3 is a detail of the type of shutter shown in Figure 1;

Figure 4 is a detail;

25 Figures 5, 6 and 7 illustrate variant forms of incandescent globe or bulb which may be employed with my device, Figure 5 illustrating one which is adaptable to the design illustrated in the parts of Figures 1 and 3;

30 Figure 8 illustrates a form of exterior shade with an ornamental design thereon;

Figure 9 illustrates a moving shutter appropriate for use with the shade of Figure 8; and

35 Figure 10 illustrates a form of bulb appropriate for use with the members shown in Figures 8 and 9;

Like parts are indicated by like symbols throughout the specification and drawings.

40 Referring to the drawings and considering first the form of Figures 1 to 5, A generally indicates any suitable base upon which may be mounted a translucent shade A¹ which may be provided with any suitable illustrative designs and may for example include water portions A², land portions A³ and the moon A⁴. It will be understood that the member A¹ is fixed. It may support any suitable cover or top member A⁵.

45 Referring for example to Figures 1 and 5,

B generally indicates an incandescent bulb having the screwthreaded portion B¹ adapted to fit into the usual electric light socket B². B³ indicates the usual wiring connection adaptable for insertion by means of the plug B⁴, into any suitable electric power outlet. The lower portion of the bulb B is irregularly formed or grooved as at B⁵ in order to break up the light which is delivered to the portion A² of the outer screen A¹. It will be noted that the interior of the portion A², in line with the irregularly formed portion B⁵ of the globe B is also irregularly formed as at B⁶. This formation of the globe and of the inner surface of the screen member A¹ in cooperation with the exterior water design on the screen A¹, tends to give an effect indicating the reflection of light upon water. The upper portion of the bulb may be formed with a design generally corresponding to the design upon the screen A¹. For example in alignment with the land portions A³ of the screen I may illustrate more or less opaque portions B⁷ of the bulb B. In line with the moon A⁴ is the moon B⁸, in the shape of a spot of clear glass through which light freely passes, the rest of the surface of the bulb B being less translucent, in varying degree. Note also that the degree of translucence in the portion B⁵ of the bulb B may be varied. For example the bottoms of the individual grooves or troughs may be either more or less translucent than the tops, thereby obtaining an uneven distribution of light such as is characteristic of moonlight upon water. Referring again to Figure 1, C indicates a pivot support terminating in a point C¹ adapted to penetrate an aperture C² in the center of the top frame C³ from which depends the light pervious shutter structure C⁴. This structure is shown in the form of a cylinder having a lower portion C⁵ provided with diagonal lines or bands or strips C⁶ of varying translucence. The upper portion of the member C⁴ may be provided with a design including clouds C⁷ on a sky background C⁸.

When the parts are in the position in which they are shown in Figure 1 and the electric light is lighted, the heat of the light

causes the air to flow upwardly through the base A and within the shutter C⁴ into contact with the fan members C⁹, whereby the upward flow of heated air causes a rotation of the shutter member C⁴. The heated air 5 may flow upwardly through the shutter members D D¹ provided with opposed apertures D². Since the members D, D¹, as shown in Figure 4, are relatively rotatable, the degree of overlap of the apertures may be controlled 10 and thereby the speed of upward circulation of the heated air thus providing controlling means for the speed of rotation of the shutter C⁴. It will be realized that when the shutter C⁴ rotates it passes between the bulb B and the outer member A¹. The shutter may 15 be entirely translucent, but of varying degrees of translucence, the effect of its rotation will be to cause the appearance of clouds floating across the sky portion of the design 20 shown in the member A¹. The inclined strips C⁶, passing between the relief portions B⁵ and B⁶ of globe and shutter, cooperate in giving a very lifelike imitation of the reflection 25 of moonlight upon rippling or moving water. The clouds will give appearance of occasionally passing over and partially obscuring the moon.

This particular design is merely illustrative and I do not wish to be limited to any specific design. For example I may employ the design shown in Figures 8, 9 and 10 in which the member A¹ is formed with a lower water section E, a waterfall E¹, the boiling 30 whirlpool or agitated water E² at the base of the waterfall and the cloud covered sky E³ above the fall, with mountains or rocks E⁴ at one side. In order to assist in obtaining the realistic water effect I undulate or 35 otherwise relieve the inner surface of the member A¹ as at E⁵. In the place of the generally smooth bulb of Figure 5 I may employ the bulb of Figure 10 which carries substantially the same design on it, either in 40 color or in relief as is carried on the outer screen of Figure 8. This bulb may have the water undulations or relief G, a portion G¹ corresponding to the waterfall, the portion G² corresponding to the portion E² of the 45 screen, the cloud covered sky G³ and the rocks or mountains G⁴. Preferably the design is helped out in relief, the undulating character of the water being clearly illustrated in Figure 10. However, the same effect 50 may be obtained at least partially by merely varying the translucence and color of the various parts of the design.

I may employ with the screen and bulb of Figures 8 and 10 a shutter including the lower water portion H having inclined or 55 spiral lines of varying color and translucence. A smaller band H² is aligned with the disturbed water E² or G² at the base of the waterfall. The band H² in the shutter is represented by rather sharply inclined bands

of varying color or translucence, inclined in opposition to those of the water band as indicated at H. H¹ is a band in alignment with the waterfall E¹ and H³ is a band of sky flecked with clouds. In the operation of 70 the device the rotation of the shutter between the bulb and the outer screen results in a very lively and realistic imitation of flowing water in the lower portion of the picture, a waterfall and a whirlpool or surge of water 75 at the base of the waterfall, with clouds actually passing over the sky above.

The bulbs I and I¹ of Figures 6 and 7 merely illustrate different types of bulb which may be employed to obtain different 80 effects. For example the bulb of Figure 7 is useful in obtaining an effect of falling rain whereas the bulb of Figure 6 fits well into fire scenes.

It will be realized that whereas I have described and shown a practical and operative device, nevertheless many changes might be made in the size, shape, number and disposition of parts without departing from the spirit of my invention. I therefore wish my 90 description and drawings to be taken as in a broad sense illustrative and diagrammatic rather than as limiting me to my specific showing.

The use and operation of my invention are 95 as follows:

I find it desirable in providing a display device to give the illusion of moving parts in a picture, to employ a fixed screen, herein shown as a cylindrical outer screen, and a light source. I place between the screen and the light source a moving shutter. Preferably I position within the moving shutter and about the light source a second fixed 100 screen, which may be the glass or envelope of the light source itself. I prefer to form or mark the bulb to conform to and help in the illustration of the desired picture. This is illustrated in Figures 5, 6, 7 and 10. I 105 may do this in relief or by varying translucence or by variation in color or by any desired combination thereof. I have illustrated as examples the employment of bulbs having undulating water portions, fire portions 110 and the like.

I also find it desirable to form one or both faces of the outer screen in relief. I have herein illustrated the relief as applied only to the inner face. In general this is preferable as it permits a smooth, for example, cylindrical face, for the display of the picture. On the other hand I do not wish to be limited to the employment of relief on the inside only or to the employment of relief at all.

Preferably I avoid the employment of opacity. For example my bulb may have no opacity whatsoever. This is to be preferred, since opacity merely cuts off and wastes light and I can obtain my desired ef 130

fects of light and shade or of light and dark mainly by varying or contrasting translucence. The shutter C⁴ also is preferably free of opaque portions and while I do not wish 5 to be limited specifically, except so far as I limit myself by my claims, to an arrangement in which opacity is not employed, I find that on the whole variation in translucence is to be preferred.

10 I claim:

1. In a display device, a light source, a translucent exterior display member carrying a picture having portions representing fixed objects and other portions representing 15 objects in motion, the various portions of said picture being of varying translucence and color, a normally fixed, translucent screen interposed between said light source and said display member, said screen being 20 of varying translucence and being adapted to cause the projection upon the translucent display member of light varying in intensity in relation to the different parts of the picture, and a moving translucent screen, 25 interposed between said fixed screen and said translucent display member, said moving screen including portions of varying translucence and being adapted to cause, in response to its movement, an appearance of 30 motion upon the translucent display member, said display member and fixed translucent screen including surfaces having portions in relief, in association with the picture.
- 35 2. In a display device, a circumferential translucent screen having a design on the exterior surface thereof, the interior surface being formed in relief in relation to said design, a light source within said circumferential screen and a moving light pervious screen interposed between said circumferential screen and said light source, said moving screen having associated therewith design portions relating to the design upon the 45 circumferential screen.
3. In a display device, a translucent screen having a picture thereon and an incandescent bulb associated therewith, said bulb being provided with relief portions having relation to the picture on said screen.
4. In a display device, a translucent screen having a picture thereon and an incandescent bulb associated therewith, said bulb being provided with relief portions having relation to the picture on said screen, and a moving light pervious screen member positioned 55 between the screen and the bulb.

Signed at Chicago, county of Cook and State of Illinois, this 5th day of June, 1931.

ALFRED H. ZELEDON.
